Attnys.

UNITED STATES PATENT OFFICE.

PERSON NOYES, OF LOWELL, MASSACHUSETTS.

GAS-PRESSURE REGULATOR.

SPECIFICATION forming part of Letters Patent No. 241,057, dated May 3, 1881.

Application filed April 19, 1880. (No model.)

To all whom it may concern:

Be it known that I, PERSON NOYES, of Lowell, in the county of Middlesex and State of Massachusetts, have invented certain Improvements in Gas-Pressure Regulators, of which the following is a specification.

This invention relates to gas-pressure regulators for street-mains and other large pipes or conduits for gas in which the regulator is composed of a casing, through which the gas is adapted to pass, leaving a rigid valve-seat, a floating inverted cup or holder adapted to be raised or supported by the pressure of the gas intervening between the regulator and the burners, and a valve supported by and floating with the holder and adapted to close upwardly against the valve-seat to shut off the flow of gas through the regulator. In this class of regulators it is desirable that the floating holder should exert a pressure upon the gas in the pipes between the regulator and the burners, and such pressure should increase as the quantity of gas passing increases, and vice versa, so as to compensate for the obstruction to the flow of gas resulting from the friction of gas on the pipes, the friction increasing with the quantity passing.

My present invention has for its object to assist the action of automatic machines of this class, and it also has for its object to control or fix the pressure of the floating holder at any desired point. To this end I make use of certain details of construction and arrangement of parts, which I will now proceed to more specifically describe.

In the accompanying drawings, which form part of this specification, Figure 1 represents a vertical section of an automatic gas-pressure regulator embodying my invention. Fig. 1^a represents a horizontal section of the mercury-holder forming part of the compensator attached to said machine upon the line *x x*, Fig. 1. Fig. 1^b is a modification in the construction of a part of said machine. Fig. 2 represents a gas-pressure regulator of another form, embodying a portion of my invention.

In these figures the same letters refer to the same parts.

In the drawings, D represents a casing to be placed in the ground and connected with the gas-main. The arrows show the course of the

gas into the inlet A, through the valve B, and out from the outlet C.

E represents a casing placed in a building (in this case directly over the casing D) enclosing the floating gas-holder F, in form like an inverted cup. This gas-holder is provided with a water seal, *w*, between its walls and the walls of the casing E.

g is a rod connecting the gas-holder F with the upwardly-closing valve B and its depending telescopic tube *d*. This rod has a telescopic tube, *d*², depending from it, closed at its upper end, and projecting at its open lower end into a seal of mercury or other suitable fluid in an annular receptacle formed by two concentric tubes, *d*³ *d*⁴, through the former of which the rod *g* passes. The valve B has a telescopic tube, *d*, projecting downwardly into a glycerine or other fluid seal contained in an annular receptacle, *a*.

G is an automatic compensator attachment, for increasing the pressure of the floating gas-holder F to any point desired. This compensator consists of the double-conical tube T, 7^b containing mercury, depending from the bar *k*, to which it is connected by the links *n n*. The bar *k* is connected at one end with the rod *g*, and it is pivoted upon the fulcrum *h*, so that when tilted upon this fulcrum the mercury may be transferred from one end to the other of the holder T, and so made to force down or lift up the gas-holder F and valve B, the operation being substantially as described in my pending application for Letters Patent 8^c for improvements in gas-pressure regulators filed March 19, 1879.

R is a pipe connecting the main pressure with the inside of the gas-holder F.

In apparatus of this class it has been the custom heretofore to include the main valve connecting with the gas-main and the floating holder in one and the same casing.

In my invention herein described I separate the valve and the floating holder, inclosing each within its own casing, and connect the valve with the holder by means of the rod *g*, as previously explained. By so doing it is possible to place the holder in any of the upper stories of a building while the valve itself is located in immediate connection with the gas-main.

The operation of this apparatus is primarily such as is common in apparatus of this class; but I make use of the following improvements:

In order to secure more perfect automatic action in the apparatus, I employ an improved form of valve-seat, giving it the form of a truncated cone or ovoid section, *f*, whereby the flow of gas through the valve may be more accurately and closely regulated. I also make use

- 10 of the modified form (shown in Fig. 1^b) consisting of the hemispherical valve-seat *f'*, having its upper portion enlarged, as shown, it being apparent that a valve-seat so formed will answer the same purpose as an ovoid valve-seat, the object in either case being to demand a more considerable vertical motion of the valve when the flow of gas approximates a minimum, and less as it approaches a maximum, by which the transference of the mercury in
- 15 the holder *T* may be made to give any desired pressure for a given flow of gas.

The pipe *R* is provided with a cock, *p*, and is also connected with an outlet-pipe, *r*, having the cock *p'*. If an increased pressure is desired, 25 a portion of the gas flowing into the holder is allowed to escape through the valve *p'* and the pipe *r*, thus reducing the pressure beneath the holder *F* and allowing it to descend and open the valve *B*, and so increase the pressure upon 30 the gas in the pipes between the apparatus and the burners. The gas allowed to escape through the pipe *r* may be burned, if desired. The pipe *r'* on the opposite side of the holder *F* may be similarly used as an outlet-pipe for increasing 35 the pressure, if desired. By means of these outlet-pipes *r* and *r'* and their cocks *p'* *p'*², the pressure of the floating holder may be controlled and fixed at any desired point independently of the action of the compensator *G*, 40 and so rendering it possible to temporarily dispense with the use of same; and the application of pipes so arranged to apparatus of this class forms an important part of my present invention. The outlet-pipes also enable the 45 valve to be suddenly opened to its fullest extent in cases of emergency. In Fig. 2 is shown this part of my invention attached to a gas-pressure regulator having a regulating gas-holder, *F*, in combination with an annular valve, as described in Letters Patent of the 50 United States No. 209,407, issued to M. W. Kidder, and dated October 29, 1878. It is possible, by means of my invention so applied, to more exactly modify and control the action of 55 the valve *B* and avoid the necessity for the compensator and weights heretofore used.

It is obvious that the pipe *r* may be in connection with the pipe *R*, as shown, or may be independent of said pipe, as shown by *r'*, as 60 may be desired.

In constructing the mercury-holder *T*, I make use of the improved form more fully shown in Fig. 1^a, the holder being narrowed at or near the middle thereof for the purpose of preventing a sudden movement of the mercury from 65 one side to the other of the holder. This form of the holder and the employment of the pipe *R* enable any desired form of valve to be employed, as ovoid or flat.

It is obvious that my improved form of valve-seat previously described is equally applicable to any form of regulator.

A pressure-regulator constructed on the general principles herein described may be used for steam, air, or water without other changes 75 than those which would naturally occur to a mechanic in adapting it to the nature of the fluid or liquid, particularly when constructed as shown in Fig. 2.

Having thus described my invention, what I 80 claim, and desire to secure by Letters Patent, is—

1. The combination of the valve-chamber *C*, having a valve, *B*, the floating holder *F* in the casing *E*, the automatic compensator attachment *G*, the connecting-rod *g*, connecting the valve-floating holder and compensator, and the pipe *R*, connecting the valve-chamber and the interior of the floating holder, and provided with an outlet-pipe, whereby the pressure of 90 the floating holder may be controlled and fixed at any desired point.

2. In a gas-pressure regulator, the combination of the valve-chamber *D*, containing the upwardly-closing valve *B*, having a sealed telescopic tube, *d*, the floating gas-holder *F*, contained within the casing *E*, the supply-pipe *R*, the automatic compensator attachment *G*, and the connecting-rod *g*, having the sealed telescopic tube *d'*, substantially in the manner and 100 for the purpose set forth.

3. In a gas-pressure regulator, the conoid or ovoid valve-seat *f*, in combination with an annular valve and a hollow liquid-loaded compensating-weight narrower at its center than 105 at its ends, as set forth.

4. In a gas-pressure regulator, the outlet-pipe *r*, leading from the gas-holder and provided with the cock *p'*, substantially as described, and for the purpose set forth.

In testimony whereof I have signed my name to this specification, in the presence of two subscribing witnesses, this 15th day of April, A. D. 1880.

PERSON NOYES.
